UNITED STATES PATENT OFFICE.

HERBERT E. IVES, OF MONTCLAIR, NEW JERSEY, ASSIGNOR TO WESTERN ELECTRIC COMPANY, INCORPORATED, OF NEW YORK, N. Y., A CORPORATION OF NEW YORK.

TRANSMISSION OF PICTURES BY ELECTRICITY.

Application filed March 18, 1926. Serial No. 95,578.

This invention relates to the transmission of pictures by electricity and more especially to a novel optical arrangement suitable for use in such systems.

5 The invention is in the nature of an improvement upon the system disclosed in the application of H. E. Ives, Serial No. 711,755, filed May 8, 1924. In that application there is disclosed an electromagnetic light valve 10 of the single string type for controlling the exposure of elemental areas on a photosensitive receiving film. The size of the exposed elemental areas is determined by certain aperture forming elements which constitute integral parts of the light valve proper. These elements comprise a vibrating string, a fixed aperture in the light valve pole-piece and an adjustable aperture or set of "jaws" for controlling the effectiveness of 20 the received currents. Because of the proximity of these elements and because of the delicacy of the vibrating string, the adjustment of such a valve, as regards the degree of exposure to be attained, is sometimes difficult.

It is an object of this invention therefore to improve the efficiency of picture reproducing mechanisms by providing an optical system which is characterized by simplicity 30 of organization and ease of adjustment.

Another object is a method for exposing a photosensitive receiving surface in equal successive areas to light uniformly distributed over each area and with an intensity determined by received picture currents.

35 A feature of the invention relates to a combination of light controlling apertures and lenses for determining the character and size of elementary exposed areas of a receiving film, as well as the particular portion of a received carrier wave to be effective in the picture reproduction.

Other features and advantages of the invention will be apparent upon a consideration 45 of the description given hereinafter and as pointed out in the appended claims.

It is to be understood that the terms used herein in reference to a picture both in the specification and claims do not limit this invention to the production of a picture record at the receiver from a picture record at the transmitter. The invention is equally applicable to systems, for example, in which a transitory image of a still or moving pic-

ture or object is produced at the receiver, 65 as in certain forms of television systems.

The term "light" as used herein includes not only radiations within the visible spectrum, but also radiations having wave lengths above and below those of the visible 60 spectrum.

Referring to the drawing Fig. 1 shows, schematically, apparatus and circuits at both the sending and receiving stations of a picture transmission system embodying the 65 present invention.

Fig. 2 is a detailed showing of the relation between the light valve apertures and the vibrating string.

Fig. 3 is a detailed showing of the device 70 for adjusting the size and character of the exposure on the receiving film.

Fig. 4 is a detail of other adjusting means for determining the "bias" or what particular portion of the curve of the received current will be effective in reproducing the picture.

The same reference characters are used in the several figures to indicate corresponding elements.

Referring to Fig. 1 an amplifier-modulator 1 is supplied with carrier currents from a source 2, and with picture currents from a photoelectric cell 3. The output of the amplifier-modulator 1 is impressed upon the line 11, after passing through a filter 4. The photoelectric cell 3 is located within the transparent drum 5 which is driven in any suitable manner from shaft 6. Mounted on drum 5 is the picture 7 in the form of a 90 film. Light from source 8 is focused by means of lens 9 upon the picture film after passing through an aperture in the screen 10. The amount of light reaching cell 3 is determined by the transparency of the particular element which happens to be in alignment with the opening in screen 10 and the light from source 8. The amount of light incident upon the active element of cell 3 in turn determines the amplitude of current 95 which is impressed upon the modulator 1. Thus, the currents from source 2 are modulated in accordance with the characteristics of the successive elements of the picture film which is scanned in a continuous helical 100 path.

Referring to the receiving station shown schematically in the lower portion of Fig. 1,

the modulated carrier currents from line 11 after passing through filter 12 are amplified by device 13 and are impressed upon the string 16 of the light valve 17. The string 16 is suspended within the valve 17 so as to vibrate in the direction of the trace on the receiving film 29. The optical system for the receiving station is shown schematically in horizontal section.

Light from source 18 is directed by means of lens 24 upon the string 16. The lamp 18 is preferably of such a type as to intensely and uniformly illuminate the opening 19. The light valve 17 comprises a winding 25 which is mounted on a hollow central core of the magnetic frame 26. A plate 27 is fastened to the frame 26 and provides an air chamber within which is located the string 16. String 16, therefore, vibrates before the opening 19 in the light valve pole-piece and before the opening 28 in plate 27. The position of string 16 with relation to the openings 19 and 28 is shown more clearly in Fig. 2. This position of the string may correspond to a completely transparent element of the picture being transmitted. The reproducing film 29 is mounted upon drum 30 which is driven from shaft 31 in a manner identical with the driving of drum 5. For the purpose of controlling the exposure of film 29, a series of adjustable plates is interposed between the light valve 17 and the film 29. One of these plates, namely baffle plate 20, is shown in detail in Fig. 3. This plate has an opening 23 in the central portion thereof which is adapted to be placed in alignment with the opening 28 of the light valve and the opening between the plates 32 and 33. Baffle plate 20 is riveted or fastened in any desired manner to the bracket 34. Bracket 34 is suitably mounted upon the main frame 35 and may be adjusted in a vertical or horizontal direction by means of the adjusting screws 36 and 37, respectively. For the purpose of controlling the effective horizontal width of opening 23 there is provided a vane 22 which may be adjusted horizontally in the guide before the opening 23 by means of the adjusting screw 38. On the side of the plate 20 opposite to vane 22 there is positioned another vane 21 which may be adjusted vertically in the guides 52 by means of adjusting screw 39. By means of screws 38 and 39 therefore the effective area of the opening in plate 20 may be readily varied. Interposed between the plate 20 and the receiving film is a set of plates 32, 33 as shown in Fig. 4. Plates 32 and 33 are arranged to be moved towards, and away from each other by means of the adjusting screws 41 and 42, and are so mounted that the opening between them is parallel to and in alignment with light valve string 16. Between the light valve and the baffle plate 20 is positioned a lens 43 which focuses an image

of string 16 upon the slit between plates 32 and 33. Similarly, between the plates 32 and 33 and the receiving film 29 is interposed lens 44 which focuses an image of the adjustable opening in plate 20 upon the receiving film 29.

Since lens 44 focuses upon the opening in plate 20, the size of the elemental exposure of film 29 is determined by the effective opening in plate 20 which may be controlled as hereinbefore mentioned by means of the adjusting screws 38 and 39. Since this opening is not near the focal point of lens 43, said opening is always uniformly illuminated by the light passed through valve 17 and is of an intensity determined by the amplitude of vibration of string 16. Furthermore, since lens 43 focuses an image of the string 16 upon the opening between the plates 32 and 33 the image of said string acts as a shutter before this opening thus controlling the amount of light passed through said opening upon the receiving film.

For the transmission of pictures, the communication between the sending and receiving stations may be made by means of a carrier channel or a radio telephone channel instead of the transmission line 11, which is shown. The sending drum 5 and receiving drum 30 are rotated in synchronism by any suitable means such as that described in the co-pending application of M. B. Long, Serial No. 681,347 filed December 18, 1923. These drums are not only rotated in synchronism but are also moved axially along the respective shafts 6 and 31. As the drum 5 rotates, carrier current from source 2 is modulated according to the varying tone values of successive elemental areas of the picture 7 and are sent over the transmitting channel to the receiving station where the modulated waves are impressed upon the string 16 of light valve 17. Assume that the normal position of string 16 is such that an image of said string is focused by means of lens 43 to cover the aperture between plates 32 and 33, as shown more clearly in Fig. 4. In this condition the receiving film 29 is unexposed. As string 16 vibrates in response to the received waves, the image of said string correspondingly uncovers the aperture between plates 32 and 33 allowing a proportionate amount of light to reach the film 29. The size of the exposed areas on film 29 may be adjusted by means of screws 38 and 39. This exposed area will therefore bear a definite relation to the size of the effective opening in plate 20 and will be uniformly illuminated.

As mentioned above, when string 16 is at rest, plates 32 and 33 may be adjusted so that the image of string 16 just covers the opening between the plates, or the plates may be so adjusted that an appreciable move-

ment of the string is necessary before the receiving film is exposed. The adjustability of jaws 32 and 33 therefore permits the selecting of any portion of the incoming wave 5 to cause the exposure of the record blank. For example, if the plates 32 and 33 are so adjusted that the distance between them is equal to the width of the projected image of string 16, exposure of film 29 begins just 10 as soon as string 16 begins to move. If the aperture between plates 32 and 33 is less than the width of the projected image appreciable movement of the string must take place before exposure begins. From the 15 foregoing description it will be seen therefore that the size and character of the elemental exposed areas of the receiving film as well as the effective portion of the received carrier waves may be readily adjusted 20 at points external to the valve proper.

What is claimed is:

1. In a system for the transmission of pictures, a receiving station, a drum at said station said drum carrying a photosensitive 25 producing surface, means for transmitting to said station a carrier wave modulated according to characteristics of a picture or object, an image of which is to be produced, a light valve, and means external to said 30 valve comprising a plurality of lenses and adjustable apertures for controlling the exposure of said surface according to the received waves and for determining the portion of said waves effective in such exposure.
2. In a system for the transmission of pictures by electricity, means for modulating carrier waves according to the characteristics of a picture or object, an image of which is to be produced, means for impressing said 40 waves on a light valve, said light valve having a string shutter element responsive to the impressed waves, a receiving drum carrying a photosensitive reproducing surface, plates having an adjustable aperture there- 45 between, means controlled by said string for illuminating said aperture with light of an intensity corresponding to the picture or object characteristics, and means for determin- 50 ing the portion of the received waves effective in the production of an image of said picture or object, said last mentioned means comprising a lens for projecting an image of said string on said aperture.
3. In a system for the transmission of pictures by electricity, means for modulating a carrier wave according to tone values of successive elemental areas of a picture or object, an image of which is to be produced, means for impressing said modulated waves upon a 55 single string light valve, an element carrying a photosensitive reproducing surface, plates located between said valve and said surface and having an adjustable aperture therebetween, means for determining the portion of a received wave effective in the production 60

of the image of the picture or object, said last mentioned means comprising an optical system for projecting an image of said string on said aperture, and means for adjusting the relation between said plates and said 70 string image.

4. In a system for the transmission of pictures by electricity, carrier waves modulated in accordance with tone values of successive elements of a picture or object, an 75 image of which is to be produced, a moving light sensitive record blank, a source of light for said blank, a light valve having a movable string, means external to said valve for providing an adjustable aperture parallel 80 with said string, means for producing an image of said string at said aperture, said image completely covering said aperture when said string is at rest, a light baffle between said plates and said valve and having 85 adjustable opening means controlled by said string for uniformly illuminating said opening with light of an intensity determined by the received waves, and means comprising the image projected on said aperture for 90 controlling the portion of the received waves effective in the production of the image of the picture or object.

5. In combination, a light valve having a single string, a light baffle having a slit 95 therein, a source of light, another light baffle having an opening therein parallel with said string, an element with a photosensitive surface, means for producing an image of said string at said slit, said image completely screening said surface when said string is at rest, means effective according to the amplitude of movement of said string to illuminate the opening in the first mentioned baffle, and means for adjusting the width of 105 said slit to determine the particular amplitude of movement of said string at which the exposure of said surface takes place.

6. In combination, a light valve, having a single string, a carrier wave modulated according to picture or object characteristics, means for applying said carrier wave to the light valve to cause a movement of the string proportionate to the amplitude of said wave, an element having a photosensitive surface, 110 means for exposing said surface as soon as said string begins to move, and means comprising an optical system and a plurality of adjustable plates between said valve and said surface for varying the degree of amplitude of said string necessary to expose 115 said surface.

7. In a picture transmission system, the combination of a light valve having an aperture and a movable shutter, a photosensitive element, a light screening device having an opening therein, a source of light, means for controlling said valve by received picture currents to move said shutter to correspondingly allow light rays to pass through 125 130

5 said light valve aperture; means for focusing said rays at a point between said screen and said photosensitive element to uniformly illuminate said opening, and means for focusing an image of said illuminated opening upon said element.

8. In an electro-optical image producing system, a source of image producing currents, a light valve having a shutter movable under the influence of currents from said source, an element upon which an image is to be produced, a source of light of constant intensity, a first lens producing an image of the light valve shutter at a point

15 between said shutter and said image element, a light screening device having an opening therein and located between said shutter and the image of the shutter produced by said first lens, and a second lens producing an image of said opening on said 20 image element, whereby an elemental area of said image element is uniformly exposed to light from said light source of an intensity determined by the movement of said shutter.

10 In witness whereof, I hereunto subscribe 25 my name this 16th day of March A. D., 1926.

HERBERT E. IVES.
